UNITED STATES PATENT OFFICE

EDWARD O. ELLIOTT, OF JENKINTOWN, PENNSYLVANIA

LOCOMOTIVE BOILER SUPPORT

Application filed December 6, 1929. Serial No. 412,211.

My invention relates to certain improvements in locomotive boiler supports, and this application is a companion application to that filed by Henry K. Harwick on November 9, 1929, under Serial No. 405,994.

The object of the present invention is to reinforce the frame of the locomotive by a boiler support which extends above the frame and is an integral part of the frame, and to provide saddles which are secured to the boiler and which are arranged to slide upon the boiler support.

The invention also relates to certain details of construction of the saddles as described in detail hereinafter.

In the accompanying drawings:

Fig. 1 is a side view of sufficient to a frame of a locomotive showing the boiler support and the saddles detached from the boiler, the outline of the boiler being shown in dotted lines;

Fig. 2 is a plan view;

Fig. 3 is a transverse sectional view on the line 3—3, Fig. 1;

Fig. 4 is an enlarged sectional view on the line 4—4, Fig. 1; and

Fig. 5 is a detailed view showing one of the pads on the flange of a longitudinal web.

Referring to the drawings, 1—1 are the side frames of a locomotive, having the usual pedestals 2 which are cast integral with the side frames. Transverse members 3 tie the two side frames together at intervals. The entire structure is made as an integral casting but it will be understood, however, that the side frames may be of any type desired and that the cross members may be arranged in any manner without departing from the essential features of the invention.

Cast integral with the frame structure is the boiler support, which, in the present instance, consists of two longitudinal webs 9 and transverse members 4. These transverse members are arranged at intervals throughout the length of the frame and have laterally extending webs 4a extending from the longitudinal webs 9 to points on the main frame, so as to reinforce the web 9 and to materially increase the strength of the entire structure. By extending the boiler support

a considerable distance above the main frame, the vertical depth of the frame is increased and strengthened and the depth over the pedestals is increased, permitting a lighter construction of the entire frame. At the upper edge of each longitudinal web 9 is a flange 10 and at intervals this flange is enlarged to form raised pads 11 (Figs. 4 and 5). The flanges 10 materially strengthen the longitudinal webs and connect the several pads 60 which carry the boiler.

These segmental flanges 6 of the saddles are secured to the boiler *a* by rivets or studs, or they may be welded thereto if desired. 7 is a pad which is located between the flanges 6 of the saddles 5 and the boiler as shown in Fig. 3.

Each saddle is made as shown in Figs. 3 and 4 and has a portion 12 which is directly above the upper surface of the pad 11, and between this pad 11 and the portion 12 of the saddle 5 is a gib 13, which provides a renewable wearing surface and also facilitates finishing in this shop as this gib is applied after the saddle is attached to the boiler. 75 These gibs have lips at both ends to retain them in place and are held transversely of the locomotive by tap bolts 14 in the present instance. Each saddle has a depending portion 15 which is opposite the edge of the pad 11, and between this extension and the edge of the pad is a gib 16 having lips at each end for retaining it in position on the saddle and this gib provides a renewable wearing surface.

A cap plate 17 is secured by a stud bolt 18 to the underside of the extension 16 of the saddle and this cap acts to prevent upward movement of the boiler. In order to prevent the cap 17 from clamping the pad 11, one or more liners 19 are introduced between the cap plate and said extension of the saddle. In the present instance, I have shown 3 saddles on each side of the boiler support of the locomotive and these saddles are secured to the boiler in the manner shown and are free to move longitudinally with the boiler on the boiler support, to allow for expansion and contraction. This boiler support, as stated above, is, in the present instance, an 100

integral part of the main frame of the locomotive.

I claim:—

1. The combination in a locomotive, of a main frame; a boiler support thereon projecting above the forward frame and consisting of two longitudinal webs spaced apart; pads on the webs; and saddles on the boiler arranged to slide on the pads of the boiler support.
2. The combination in a locomotive, of a main frame; a boiler support extending above the main frame having a longitudinal flange; pads arranged at intervals on the flange; and saddles arranged to be secured to a boiler and to slide on the pads.
3. The combination in a locomotive, of a main frame; integral boiler supports extending above the main frame, the support consisting of longitudinal webs and transverse members connecting the webs, each longitudinal web having a flange at its upper end; and a series of saddles arranged to be secured to the boiler, said saddles being located directly above the flanges of the webs and having cap plates extending under the webs.
4. The combination in a locomotive, of a main frame; integral boiler supports extending above the main frame, each support consisting of longitudinal webs and transverse members connecting the webs, each longitudinal web having a flange at its upper end; a series of saddles arranged to be secured to the boiler, said saddles being located directly above the flanges of the webs and having cap plates extending under the webs; gibs carried by each saddle and located between the upper surface of the flange of the cap and the saddle; and a second gib bearing against the edge of the flange.
5. The combination in a locomotive, of a main frame; a boiler support forming an integral part of said main frame and consisting of two longitudinal webs spaced apart and connected together by transverse members, each longitudinal web having a series of pads at its upper edge; a series of saddles secured to the boiler and located above the pads of the boiler support, said saddles having depending portions projecting at the edges of the pads; a gib mounted between the saddle and the upper surface of a pad; a second gib mounted between the depending portion of the saddle and the edge of the pad; and a cap plate secured to the saddle and extending under the pad, said pads being arranged so that the saddles can slide freely on the pads.
